DESIGN FOR A MATERNITY GARTER SUPPORT

Lois R. Hamilton, Los Angeles, Calif.

Application January 17, 1947, Serial No. 136,200

Term of patent 3½ years

(Cl. D20—2)

To all whom it may concern:

Be it known that I, Lois R. Hamilton, citizen of the United States and residing at Los Angeles, in the county of Los Angeles, State of California, have invented a new, original, and ornamental Design for Maternity Garter Support, of which the following is a specification, reference being had to the accompanying drawing, forming part thereof, in which:

Fig. 1 is a front elevational view of a maternity garter support, showing my new design;

Fig. 2 is a side elevational view of the maternity garter support shown in Fig. 1;

Fig. 3 is a rear elevational view; and

Fig. 4 is a front perspective view thereof.

I claim:

The ornamental design for a maternity garter support, substantially as shown.

LOIS R. HAMILTON.
